William Michael

UNITED STATES PATENT OFFICE.

WALTER W. DECKER, OF MINNEAPOLIS, MINNESOTA.

NAME-PIECE FOR UMBRELLAS.

1,346,810.

Specification of Letters Patent. Patented July 20, 1920.

Application filed September 19, 1919. Serial No. 324,939.

To all whom it may concern:

Be it known that I, WALTER W. DECKER, a citizen of the United States, residing at Minneapolis, in the county of Hennepin and 5 State of Minnesota, have invented certain new and useful Improvements in Name-Pieces for Umbrellas; and I do hereby declare the following to be a full, clear, and exact description of the invention, such as 10 will enable others skilled in the art to which it appertains to make and use the same.

My invention has for its object to provide an extremely simple and highly efficient name piece for umbrellas adapted to be easily 15 interlocked thereto in such manner that it cannot be readily removed; and to such ends, generally stated, the invention consists of the novel construction and combination of parts hereinafter described and defined in 20 the claims.

The device is in the nature of a sectional sleeve made up of a channel member and a slide, adapted to be placed around the umbrella rod or stem adjacent to the handle 25 thereof and to be there secured in such manner that it cannot be removed.

The invention is illustrated in the accompanying drawings wherein like characters indicate like parts throughout the several 30 views. Referring to the drawings;

Figure 1 is an elevation showing a portion of an umbrella and showing my improved name piece interlocked to the stem thereof;

Fig. 2 is a perspective view of the name 35 piece showing the sections thereof separated; and

Fig. 3 is a section on the line 3—3 of Fig. 1.

Of the parts of the umbrella, it is only desirable to particularly note the rod or stem 40 4, the handle 5, the spreader ribs 6, the sleeve 7, which operates to spread the ribs, and the spring latch 8 which secures the sleeve 7 in its lower position, all of the said parts being of the usual or any suitable construction.

The name piece, as indicated, is made up of a channel member 9 and a slide 10. The channel member 9 has internal grooves 11 that receive the reduced edges 12 of the slide 50 10, and permit the slide to be moved longitudinally into the channel member. Above its edge flanges 12, slide 10 has a raised portion formed with lock notches 13 that are adapted to be engaged by lock lugs 14 on the 55 intermediate portions of the inturned edges of the channel members 9. The front end

of the raised portion of slide 10 is tapered or beveled at 15 so that when the slide is forced into the channel, its end portion 15 will act as a cam to spread the lugs 14 and 60 spring the sides of the channel, as shown by dotted lines in Fig. 3, until the notches 13 are alined with the lugs 14, and whereupon the said lugs will spring into the said notches to positively lock the two elements 9 and 10 65 of the name piece together. Of course, the channel will be placed around the stem 7 of the umbrella between the handle 5 and latch 8 before the slide is driven into the same and interlocked therewith, as above described. 70 When this is done, it will be practically impossible to separate the two elements of the name piece without breaking the channel.

The owner's name may be stamped or otherwise marked on one of the sections of 75 the so-called name piece and his address or other additional matter may be applied to the other member. The marker or name piece applied as described does not in any way deface or mar the umbrella, is entirely 80 out of the way and affords a very good, simple and efficient means for marking an umbrella so that it may be identified. The marker will be held on the lower portion of the stem or rod 4 by the latch 8, and it is of 85 such length that it does not interfere with the downward movement of the sleeve 7.

To make the sections of the name piece tightly and closely fit the rod or stem of the umbrella, they are provided with internal 90 grooves of approximately semi-cylindrical extent. Preferably, also, the marker is made of nearly rectangular cross section with the corners of the channel member beveled or cut off so that in cross section the device is then given an approximately octagonal form.

What I claim is:

1. A name piece for umbrellas comprising a channel-shaped member and a slide movable in the normally open side of said channel-shaped member, said slide and the sides of said channel-shaped member having cooperating lugs and lock notches adapted to spring into interlocking engagement. 100

2. A name piece for umbrellas comprising a channel-shaped member having inturned flanges, and longitudinal grooves inward thereof, and a slide having reduced edge flanges slidable into the grooves of said channel-shaped member, and having a raised portion above its edge flanges, said internal 110

flanges and the raised portion of said slide having interlocking lugs and notches.

3. A name piece for umbrellas comprising a channel-shaped member having inturned flanges, and longitudinal grooves inward thereof, and a slide having reduced edge flanges slideable into the grooves of said channel-shaped member, and having a raised portion above its edge flanges, said internal flanges and the raised portion of said slide

having interlocking lugs and notches, the raised portion of said slide at one end being tapered to afford a cam for spreading said lugs.

In testimony whereof I affix my signature 15 in presence of two witnesses.

WALTER W. DECKER.

Witnesses:

EVA E. KÖNIG,
HARRY D. KILGORE.
